UNITED STATES PATENT OFFICE.

JOSEPH SCHMUCK, OF STEGLITZ, GERMANY, ASSIGNOR TO THE FIRM OF OPTISCHE ANSTALT C. P. GOERZ AKTIENGESELLSCHAFT, OF FRIEDENAU, NEAR BERLIN, GERMANY.

PACKING FOR LIGHT-SENSITIVE LAYER-CARRIERS.

1,000,630.

Specification of Letters Patent. Patented Aug. 15, 1911.

Application filed July 7, 1903. Serial No. 442,431.

To all whom it may concern:

Be it known that I, JOSEPH SCHMUCK, a citizen of the German Empire, and resident of Steglitz, near Berlin, Germany, have invented certain new and useful Improvements in and Relating to Packings for Light-Sensitive Layer-Carriers.

The packing and the device for changing the layer carriers therein are so constructed that as well the insertion of the packing into a box for exposing same as the removal of the layer carriers from the box after exposure can be effected in day-light.

The invention is illustrated on the accompanying drawing.

Figure 1 shows a longitudinal section through one embodiment of the new packing. Fig. 2 is a top view of the packing. Fig. 3 shows the packing of Figs. 1 and 2 inserted into a carrying frame. Fig. 4 is a longitudinal section through a modified form of the packing in connection with a modified form of a carrying frame, the carrying frame and the packing forming together a whole. Fig. 5 is a cross-section along the section line of Figs. 3 and 4. Fig. 6 is a longitudinal section through a change box into which a packing containing carrying frame in accordance with Figs. 3 and 4 may be inserted for the purpose of successively exposing the layer carriers. Fig. 7 is a top view of the change box, shown in longitudinal section in Fig. 6, showing the said carrying frame inserted therein. Fig. 8 is a longitudinal section through Fig. 7. Fig. 9 is a fragment of the device illustrated in Fig. 8, the elements of the device being shown in different position. Fig. 10 is a longitudinal section through a modified form of the packing provided with a two chambered packing room. Fig. 11 shows the packing of Fig. 10 inserted into a suitable changing and exposing box. Fig. 12 is a perspective representation of a layer carrier provided at one end with gripping openings and connected to a light-proof interposition sheet.

In the embodiment of the packing represented in Fig. 1 the layer carriers are indicated by dotted lines and designated with the reference numeral 1. The light-tight interposition sheets are designated 2. With regard to the clearness of the drawing in Fig. 1 only two layer carriers and two interposition sheets are indicated. In prac-

tice however every packing contains preferably a greater number of layer carriers and interposition sheets. The frame of the packing is open at one broad side. The light-tight closure is effected on this side by one of the light-tight sheets 2. The interposition sheets 2 extend from the package through a slit, which is light-tightly closed by a ledge 3 of velvet or like material. A springy plate 4 in the interior of the packing casing is provided for pressing the pile of layer carriers against the exposing plane. The numeral 5 designates a stop member provided at the bottom of the packing. The purpose of such stop member will be mentioned later on. 6 is a closing member at one end of the packing which is provided with extension rods 7 guided in the packing frame at the upper side of the layer carrier pile. 8 is a gripping member, firmly connected to the packing and provided with a pin 9, for fixing the ends of the light-tight interposition sheets 2 extending through the above mentioned slit of the packing. 10 is a bottom of a carrying frame or casing into which the packing can be inserted. The frame-like casing is provided with lateral guides 11 for the packing, which is carried therein, as shown in Fig. 5. The free space 12 between the bottom plate 10 and the packing inserted into the carrying frame forms a collecting chamber for the exposed layer carriers. The collecting chamber 12 is closed at the front end by a ledge 13.

In the embodiment of the packing carrying frame shown in Fig. 3 the collecting chamber can be closed at one end by a door 14 which is secured in its closed position by springy members 15.

16 is a springy pawl adapted to grasp behind the closing member 6 of the packing shown in Figs. 1 and 2.

In the embodiment of the carrying frame shown in Fig. 4 the door 14 is dispensed with, because in this instance the end member 17 of the carrying frame effects itself the closing of the packing room at one end. The carrying frame in the case of Fig. 4 therefore forms one part of the packing.

The changing and exposing box represented in Fig. 6 is provided at one end with a closing door 18 and has at its other end an opening 19 above a ledge 20, said opening forming a passage for the packing. 21 are

springs which tend to press the carrying frame with the packing against the exposing plane. 22 are springs adapted to remove exposed layer carriers from the exposing plane. 23 is a springy member being provided at its front end with a gripping mouth 24. 25 are two springs on opposite sides of the springy member 23. 26 is the dark slide of the box.

- 10 The use of the packing and the operation of its carrying frame and of the changing and exposing box is as follows: Assuming the packing being constructed in the manner illustrated in Figs. 1 and 2 of the drawing. In this instance the packing is inserted into the frame illustrated in Fig. 3, if it is intended to expose the layer carriers contained in the packing. In order to insert the packing into said frame of Fig. 3, 15 the closing door 14 is opened by pressing on the lateral springy members 15 and the packing is inserted into the opening through said door 14. Thereafter the door 14 is again closed. Packing and carrying frame 20 are now inserted into a box in accordance with Fig. 6 after opening of the door 18 of said box. After insertion of the carrying frame with the packing into the exposing box, the door 18 is again closed. The dark 25 slide 26 may now be removed. In order to free the uppermost layer carrier of the packing for exposure, the sheet 2 covering same is freed from pin 9 and drawn out. After exposure the gripping member 8 of the packing 30 is grasped and the packing drawn out through opening 19 of the box. The closing member 6 of the packing is now retained by the springy pawl 16, so that the packing room is opened. The gripping mouth 24 35 of the springy stop member 23 now grasps the front edge of the exposed layer carrier. On continued drawing out of the packing through opening 19 the springs 22 press the exposed layer carrier which is retained with- 40 in the packing room against the bottom 10 of the box. The packing is drawn out till the stop member 5 engages the ledge 13 of the carrying frame. When the packing has 45 reached this position, the layer carrier is removed so far from the packing room that its front edge can be pressed by springy member 23 and springs 25 against the bottom 10 of the carrying casing. If hereafter the packing is again pushed into the box, 50 the exposed layer carrier remains within the collecting chamber 12 below the packing. The changing operation may be repeated as often as layer carriers are contained within the packing. When all layer carriers are 55 exposed, the carrying frame with the packing are removed from the box at day-light. The packing alone may then be removed after opening of door 14 from its carrying frame within a dark chamber.

If carrying frame and packing form a 65 whole, as illustrated in Fig. 4, the exposure of the layer carriers is effected in exactly the same manner as above indicated; only the insertion of the packing into the carrying frame is dispensed with, the carrying frame 70 forming in this instance a substitute for the closing member 6.

Instead of forming the collecting chamber for the exposed layer carriers by means of a special carrying frame it is possible to 75 provide the packing itself with two chambers, as illustrated in Fig. 10 of the drawing. In this instance the layer carriers are again designated with the numeral 1, the light-proof interposition sheets with 2 and 80 the light-excluding ledge at the one end of the packing provided with the slit through which the interposition sheets 2 extend outside the packing is designated 3. 8 forms the gripping member of the packing and 9 85 the pin for fixing the interposition sheets. 4 is the springy plate within the packing room pressing the layer carriers toward the exposing plane. 6 is again a closing member. 12 is a collecting chamber below the 90 packing room, receiving the layer carriers and the interposition sheets. This collecting room forms in this instance a chamber of the packing receptacle itself. In this instance the layer carriers are shown as being provided with openings 27 at their ends remote from the gripping member 8. The openings 27 of the layer carriers are adapted to cooperate with gripping devices of a changing or exposing box for drawing the 100 layer carriers out of the packing. This embodiment of the packing therefore is designated for another construction of changing or exposing box than that represented in Fig. 6. There is however no objection to 105 combine the arrangement of a collecting chamber within the packing room with a transporting mechanism for the layer carriers of the kind above described with reference to the packing represented in Figs. 1 110 and 2.

In Fig. 11 the packing in accordance with Fig. 10 is shown partly inserted into a changing or exposing box being provided with gripping members for grasping the 115 layer carriers by entering the openings 27 of same. This changing or exposing box is open at one of its ends and provided at its other end with a door 28. 29 is a stop provided at a spring 30. 31 is a springy hook, 120 32 is a spring contacting with the lower side of said hook 31, 33 is a spring fixed to the exposing frame of the exposing box, 34 is a springy stopping hook, 35 is a hole in the bottom of the packing covered by the closing member 6 in its closing position.

The use and operation of the devices represented in Figs. 10 and 11 is as follows: The

packing illustrated in Fig. 10 is inserted into the changing and exposing box in the direction indicated by the arrow in Fig. 11. The stopping member 29 allows the closing member 6 of the packing to pass and then abuts against the front edge of said closing member 6, so that on grasping the gripping member 8 of the packing and drawing it out of the exposing chamber in the direction opposite to that indicated by the arrow in Fig. 11 the said closing member 6 is removed from the packing. The springy hook 31 of the changing box enters the hole 27 of the uppermost layer carrier, so that same is retained. When the packing is drawn out so far that the end of the layer carrier becomes free, the spring 32 contacts with the lower side of hook 31 and secures the layer carrier on said hook. On further drawing out the packing, the layer carrier is drawn out more and more from the packing room, till it finds an opportunity to pass the end of the top plate of the collecting chamber 12 and to repose on the bottom of said collecting chamber. The falling down of the end of the layer carrier on the bottom of the collecting chamber is secured by spring 33, which just in that moment assumes the position shown in dotted lines in Fig. 11, when the packing is drawn out so far that the layer carrier is freed. The drawing out of the packing is limited by the entrance of hook 34 into the opening 35 in the bottom plate of the packing. During the drawing out of the packing the light-tight interposition sheet 2 which is below the exposed layer carrier secures the layer carriers which are still contained in the packing against entrance of light. On pushing back the packing into the exposing box, the exposed layer carrier enters the collecting chamber 12. When the packing reaches the end of its returning movement, spring 32 is pressed downward, so that the layer carrier is freed by hook 31 and falls down on the bottom of the collecting chamber also with that end, which is provided with opening 27. In order to effect the exposure of the next layer carrier, the light-tight sheet 2 covering same is drawn out and the operations above mentioned are repeated. When all layer carriers are exposed, the door 28 of the exposing box is opened and the packing receptacle removed from the exposing chamber through door 28. The closing member 6 then remains in closing position, so that entrance of light into the packing room is prevented.

The provision of gripping openings or projections in the layer carriers allows a modification of the packing in such a manner that the light-tight interposition sheets of the layer carriers need not to be provided with gripping ends extending out of the packing. The light-tight interposition

sheets may be connected in this instance to 65 the layer carriers, as illustrated in Fig. 12 of the drawing, however in such a manner that the gripping openings only penetrate the layer carriers themselves, but not the light-tight interposition sheets. In this instance it is however necessary to use a modified form of a changing box.

Having now particularly described and ascertained the nature of my said invention and in what manner the same is to be performed, I declare that what I claim is:

1. A packing for light sensitive layer carriers comprising a casing provided with a slit, a pile of loose layer carriers in said casing, loose substantially straight light-proof 80 interposition sheets between the layer carriers extending through said slit which is situated in said casing directly opposite one side of said layer carriers, said interposition sheets being free from attachment with said 85 layer carriers as and for the purposes set forth.

2. A packing for light-sensitive layer carriers comprising a two-chambered casing, one of said chambers being provided with a 90 pile of loose light-sensitive layer carriers and substantially straight loose light-proof sheets interposed between same, said chamber being provided with a slit directly opposite one side of said pile through which the 95 light-proof interposition sheets extend, said interposition sheets being free from attachment with said layer carriers as and for the purposes set forth.

3. A packing for loose light-sensitive layer 100 carriers comprising a casing provided at one end with a slit directly opposite one side of said layer carriers and at the opposite end with a removable closing member, a pile of light-sensitive layer carriers within said casing and substantially straight loose light-proof sheets interposed between same, the light-proof interposition sheets extending directly in a straight line outside said casing through said slit, said interposition sheets 105 being free from attachment with said layer carriers as and for the purposes set forth.

4. A packing for light-sensitive layer carriers comprising an outer casing or frame having an opening or guideway at one end at a distance from its bottom plate, a second casing or frame inserted therein, and movable in said opening or guideway, a pile of light-sensitive layer carriers within said second or inner casing and light-proof sheets 110 interposed between the layer carriers of said pile, the inner casing provided with a slit at that end which is adapted to be drawn out of the outer casing, the light-proof interposition sheets extending through said 115 slit, the end of the inner casing opposite the end provided with the slit being open, means adapted to retain the uppermost layer 120 125

carrier within the outer casing on withdrawal of the inner casing and means adapted to transport said retained uppermost layer carrier into the free space between the inner 5 casing and the bottom plate of the outer casing.

In testimony whereof I have signed this

specification in the presence of two subscribing witnesses.

JOSEPH SCHMUCK.
